BOTTLE COVER

Filed August 31, 1925

Joseph E. Haddad

INVENTOR

BY *Victor J. Evans*

ATTORNEY

Patented Dec. 28, 1926.

UNITED STATES PATENT OFFICE.

JOSEPH ELIES HADDAD, OF LOS ANGELES, CALIFORNIA.

BOTTLE COVER.

Application filed August 31, 1925. Serial No. 53,608.

This invention relates to a bottle cover, the general object of the invention being to provide the cover with means for attaching it to a bottle mouth, the cover including a 5 rotary inner part which with the outer part, is perforated so that the contents of the bottle can pass through the perforations when they are in alignment with means for moving the inner part to place its perforations in 10 alignment with those of the outer part.

Another object of the invention is to provide spring means for normally holding the inner part with its perforations out of alignment with those in the outer part.

15 This invention also consists in certain other features of construction and in the combination and arrangement of the several parts, to be hereinafter fully described, illustrated in the accompanying drawings and 20 specifically pointed out in the appended claim.

In describing my invention in detail, reference will be had to the accompanying drawings wherein like characters denote like 25 or corresponding parts throughout the several views, and in which:—

Figure 1 is a view showing the invention in use.

Figure 2 is a longitudinal sectional view 30 through Figure 1.

Figure 3 is a section on line 3—3 of Figure 2.

Figure 4 is a section on line 4—4 of Figure 2.

35 Figure 5 is a view of the washer or ring for connecting the device with the body.

In these views, 1 indicates the neck of a bottle, such as a catsup bottle, and 2 indicates a ring or washer which is threaded to 40 engage the threaded part of the bottle mouth which is used to hold the cap of the bottle in place. This ring is formed with the lugs 3. The cap is shown at 4, and this cap has 45 its lower part fitting over the ring, and this part has openings 5 therein to receive the lugs, so that the cap is held on the body by said ring. The cap is provided with one or more holes 6 therein through which the 50 contents of the bottle pass. An inner cap 55 like part 7 fits within the outer part and has its upper end attached to a stem 8 which is 60 rotatably mounted in the end of the part 4

and is provided with a handle 9 so that it can be rotated to move the part 7 so as to place the openings 10 in said part in register with the openings 6 to permit the contents of the body to pass through said openings. Springs 11 are attached to the stem and to pins 12 carried by the part 4, these springs tending to hold the part 7 in a position with 65 its holes out of register with the holes 6 in the part 4.

From the foregoing, it will be seen that a catsup or other bottle supplied with my invention will have its contents kept covered 65 so that the contents will be kept clean. When it is desired to use some of the contents, it is simply necessary to turn the handle 9 so as to rotate the part 7 to bring its openings 10 in alignment with the openings 6 and 70 then tilt the bottle so that the contents will pass through the openings. As soon as the handle 9 is released, the spring will return 75 the parts to position where the openings 6 will be closed.

It is thought from the foregoing description that the advantages and novel features of my invention will be readily apparent.

I desire it to be understood that I may make changes in the construction and in the 80 combination and arrangement of the several parts, provided that such changes fall within the scope of the appended claim.

What I claim is:—

A bottle cover including an outer cap 85 member, means detachably connecting the cap to the bottle neck, said cap member being tapered in form and provided with a series of circumferential openings midway 90 of its ends, an inner cap member having 95 openings adapted to register with the openings in the first cap member, a stem carried by the second cap member and projecting through the end of the first cap member, pins suspended from the inner face of the closed 95 end of the first cap member and positioned between the closed ends of the two cap members, a knurled handle on the outer end of the stem, and spring members, each having one end attached to the stem and the other 100 attached to said pins in order to retain the openings out of registration.

In testimony whereof I affix my signature.

JOSEPH ELIES HADDAD.
